SUPPORT DEVICE

James A. Morrison, Rocky River, Ohio

Application September 7, 1944, Serial No. 552,985

4 Claims. (Cl. 4—185)

1

This invention relates, as indicated, to support devices, but has reference more particularly to devices of this character which are especially adapted for use as safety rails for bathtubs.

A primary object of the invention is to provide a device of the aforesaid character which may be quickly and easily installed in a bathtub, and which, when installed, is capable of resisting any and all efforts to displace the same by any pull or push which a normal individual is capable of exerting.

Another object of the invention is to provide a safety rail of the character described, which is adaptable for use in connection with bathtubs having walls of different slopes.

A further object of the invention is to provide a device of the character described having seating members which are capable of accommodating themselves to walls of any slope.

A further object of the invention is to provide a device of the character described which may be installed without the use of fastening means which are likely to injure or damage the walls between which the device is installed.

A still further object of the invention is to provide a device of the character described, which is so constructed as to readily adapt it for use as a shower curtain rod or as a clothes closet rod.

Other objects and advantages of the invention will be apparent during the course of the following description.

In the accompanying drawings, forming a part of this specification, and in which like numerals are employed to designate like parts throughout the same;

Fig. 1 is a view, partly in elevation and partly in section, of a preferred form of the device and showing the device as used for a safety rail for bathtubs;

Fig. 2 is a view similar to Fig. 1, but showing a modified form of the device;

Fig. 3 is a fragmentary cross-sectional view, showing another modification of the device;

Fig. 4 is a view similar to Fig. 3, but showing a further modification of the device;

Fig. 5 is a fragmentary cross-sectional view, showing the use of an expansion spring in connection with the device of the invention; and

Fig. 6 is a cross-sectional view, taken on the line 6—6 of Fig. 5.

Referring more particularly to Fig. 1 of the drawings, the numerals 1 and 2 represent the sides or side walls of a bathtub of conventional form and between which the device of the present invention is adapted to be mounted.

2

The device consists of a central tubular portion 3, preferably in the form of a metallic tube which is chromium-plated, a metallic cap 4 at one end, which has a slip or sliding fit over the tube 3, and a metallic sleeve 5 at the other end, which is in threaded engagement with the tube 3, the cap and sleeve being also preferably chromium-plated.

The cap 4 has a spherical socket 6 at one end which is in engagement with a seat member or stamping in the form of a metallic disc 7 having a spherical protuberance 8 with which the socket 6 is in engagement, the joint between the cap and protuberance being, in effect, a ball and socket joint. The seat member also has cemented to the rear or outer surface thereof a gasket or disc 9 of sheet rubber, approximately $\frac{1}{2}$ of an inch in thickness. The seat member is also preferably chromium plated.

The sleeve 5 is in engagement with a seat member or stamping in the form of a metallic disc 10 having a spherical protuberance 11 with which the end of the sleeve 5 is in engagement, the joint between the sleeve and protuberance 11 being, in effect, a ball and socket joint, similar to that between the cap 4 and spherical protuberance 8. The seat member is also chromium-plated and has cemented to the rear or outer surface thereof a gasket or disc 12 of sheet rubber, for the same thickness as the disc 9.

When the device is to be used as a safety rail for a bathtub, as illustrated in Fig. 1, it is located in the bathtub adjacent the faucet end of the tub, and is positioned to extend transversely of the tub, between the walls 1 and 2 thereof. The device is then expanded by rotating the sleeve 5 relatively to the tube or rail 3, so as to cause the ends of the rail to apply pressure to the spherical seats 8 and 11, thereby creating a friction or frictional pressure between the rubber discs 9 and 12 and the respective walls 1 and 2 of the tub. This friction or frictional pressure is so great as to resist any and all efforts to displace the rail by any pull or push which a normal individual is capable of exerting. The device, consequently, is well-adapted for use as a safety rail for bathtubs.

Due to the provision of the ball and socket joints, to which reference has been made, the device is adaptable for use in connection with bathtubs having walls of different slopes, the seating members readily accommodating themselves to any slope upon the application of pressure thereto by the ends of the rail.

It will be readily understood that although the

device has been described particularly with reference to its use as a safety rail for bathtubs, that it is so constructed as to readily adapt it for use as a shower curtain rod or as a clothes closet rod. In such uses, the seating members will, of course, be disposed in vertical planes.

In some cases, where the walls against which the seating members are to be disposed are sufficiently smooth, the rubber gaskets or discs may be dispensed with, and if desired, the outer surfaces of the discs may be knurled or roughened to provide frictional resistance between the discs and the walls.

In Fig. 2, a modified form of the device is shown, in which the central or rail portion 13 of the device is made of a wooden rod having a reduced end 14 to which an externally threaded metallic ferrule 15 is secured, as by a press fit, an adjustable metallic sleeve 16, similar to the sleeve 5, being secured to such ferrule. The wooden rod 13 may be coated with a suitable lacquer, or may be sheathed in a tube of plastic.

In Fig. 3, another modification of the device is shown, in which the central or rail portion 17 of the device is in the form of a metallic tube having a plastic coating or sheathing 18, and a cap or sleeve 19 is adjustably secured to the end of the tube 17, said cap having a spherical end 20 seated in the spherical seat or socket 21 of a seating member or disc 22, which has a disc 23 of sheet rubber cemented to the outer surface thereof.

In Fig. 4, a further modification of the device is shown, in which one end of the sleeve 24 is in the form of a spherical surface which is seated in a spherical seat or socket 25 of a seating member or plate 26, which has a disc 27 of sheet rubber cemented to the outer surface thereof.

It will be understood that where the various forms of the invention shown in Figs. 2, 3 and 4 are used, that the rubber gaskets or discs may be dispensed with, and, if desired, the outer surfaces of the discs or seating members may be knurled or roughened to provide frictional resistance between the discs and the walls.

In Fig. 5, a still further modification of the device is shown in which a star spring 28 is interposed between one end of the tube 3 and the cap 4, this spring serving to permit any slight expansion in the tube resulting from an increase in temperature thereof.

It is to be understood that the form of my invention, herewith shown and described, is to be taken as a preferred example of the same, and that various changes in the shape, size and arrangement of parts may be resorted to, without departing from the spirit of my invention, or the scope of the subjoined claims.

Having thus described my invention, I claim:

1. A device of the character described comprising a pair of spaced seat members consisting of discs having central spherical protuberances, a rail interposed between said members, said rail having a removable cap on one end thereof having a spherical socket engaging one of said protuberances and an adjustable sleeve on the other end of the rail engaging the other of said protuberances, the bases of said protuberances each having a considerably larger diameter than the diameter of the socket and adjustable sleeve whereby considerable portions of said spherical

protuberances are exposed to permit greater range of angular adjustment between the rail and seat members.

2. A device of the character described comprising a pair of spaced seat members consisting of discs having central spherical protuberances, a rail interposed between said members, said rail having a removable cap on one end thereof having a spherical socket engaging one of said protuberances and an adjustable sleeve threaded on the other end of the rail and engaging the other of said protuberances, said sleeve having an unthreaded portion extending from its threaded portion and overlying the rail in spaced relation thereto whereby the sleeve may be adjusted along the rail without exposing the threads on said rail to view, the bases of said protuberances each having a considerably larger diameter than the diameter of the socket and adjustable sleeve whereby considerable portions of said spherical protuberances are exposed to permit a greater range of angular adjustment between the rail and seat members.

3. A device of the character described comprising a pair of spaced seat members consisting of discs having central spherical protuberances, a rail interposed between said members, said rail having a removable cap on one end thereof having a spherical socket engaging one of said protuberances and an adjustable sleeve on the other end of the rail engaging the other of said protuberances, the bases of said protuberances each having a considerably larger diameter than the diameter of the socket cap and adjustable sleeve whereby considerable portions of said spherical protuberances are exposed to permit a greater range of angular adjustment between the rail and seat members, and spring means interposed between the end of the rail and cap and yieldably urging the cap into engagement with its protuberance so that expansion and contraction of the rail with reference to the seats is permitted.

4. A device of the character described comprising a pair of spaced seat members, each having a spherical surface, a rail interposed between said members, said rail having a removable member on one end thereof, one end of which is in engagement with the spherical surface of one of said seat members, and an adjustable sleeve on the other end of the rail engaging the spherical surface of the other of said seat members, the diameters of each of said spherical surfaces at the base thereof being considerably greater than the diameter of said removable member and adjustable sleeve, whereby considerable portions of said spherical surfaces are exposed to permit greater range of angular adjustment between the rail and seat members.

60 JAMES A. MORRISON.
